Carton Co., Chicago, Ill., a corporation of Illi-
nois

Application November 27, 1935, Serial No. 51,876

3 Claims. (Cl. 229—29)

The present invention relates to cellular cartons for packaging fragile articles such as eggs, and has particular reference to an improved type of cushion cellular carton.

5 A principal object is to provide a cushion cellular carton having a novel and effective arrangement of means for suspending the bottom portion of the carton in cushion-forming position.

10 An additional object is to provide an improved 3×4 cushion carton.

A still further object is the provision of a cushion carton having a plurality of inverted V-shaped bottom sections suspended to a series 15 of cross partitions by means of hook members extending through the walls of the bottom member in staggered relation.

These and other objects will be evident upon a consideration of the following specification and by reference to the accompanying drawings, 20 in which

Fig. 1 is a perspective view of a carton constructed in accordance with my invention;

Fig. 2 is a top view of the carton shown in 25 Fig. 1, with cover removed;

Fig. 3 is a sectional view of the carton shown in Fig. 2 and taken along line 3—3 thereof;

Fig. 4 is a view taken along line 4—4 of Fig. 2; and

30 Fig. 5 is a view of the blank from which the carton is constructed.

Within recent years the trade has become accustomed to packaging eggs in cellular cartons having a cushion forming bottom. These cartons are of the 2×6 type and the 3×4 type. 35 Customarily, the bottom member is provided with slots or openings and the cross partitions of the carton have hooks which engage the bottom member through the openings therein to maintain the bottom in cushion-forming position. In accordance with the present invention the hook members on the cross partitions are arranged in staggered relation in such a manner as to expedite the erection of the carton and engagement of the hooks without destroying the 40 stability and permanence of the securement.

45 As shown in the drawings, the carton is constructed of a single blank, cut, scored and folded to form a cover member 10 having hooks 11 along the free edge thereof. The opposite side of the cover joins a rear wall 12 along score line 13. The bottom member indicated generally at 14 50 consists of a rear inverted V-section having an upwardly and inwardly extending wall 15 joined to a downwardly and centrally extending wall 16

along score line 17, and a front inverted V-section composed of an upwardly and outwardly extending central section 18 joined to an upwardly and inwardly extending front section 19 along score line 20. The two inverted V-sections are joined together at the center of the carton along a score line 21, which is positioned at the center of the carton and slightly above the level of the front and rear walls. 5

To the outer edge of bottom section 19 a front wall 22 is joined along score line 23. The front wall is of somewhat less height than the rear wall 12 and is provided with a series of integral hinges 24. Connected to the hinges 24 are a series of transverse partitions 25 which in the erected carton extend transversely thereof to divide the carton into a series of individual cells or compartments. The opposite sides of the cross partitions 25 are joined to an attaching strip 26 by means of hinge portions 27. The attaching strip 20 is folded over and glued or otherwise secured to the rear wall 12 as will be seen particularly in Figs. 3 and 4. In the embodiment shown in the drawings, the line of attachment of the strip 26 to the rear wall is at substantially the 25 same height as the height of the front wall 22.

In its collapsed condition, the carton preferably is folded along the score line 21 in the center of the bottom section and along score lines 28, which are provided in the central portion 30 of the cross partitions, as shown particularly well in Fig. 5 and in Figs. 3 and 4.

The bottom section of the carton shown in the drawings is arranged to present three longitudinally extending channels which receive eggs positioned in the carton. This construction is provided by two complementary inverted V-sections, and the cushion-forming shape of the bottom is maintained by a hook and slot arrangement between the cross partitions and the bottom member. 35 As shown in Figs. 2 and 5, the rear bottom section 15 is provided with a series of openings 29 and the front bottom section 19 is provided with a series of similar openings 30 positioned beneath the cross partitions 25. The cross partitions are provided with projections which extend downwardly through the openings as shown in Figs. 3 and 4. These projections comprise alternate hooks 31 and hookless tabs 32. Each cross partition has a hookless tab or projection 40 on one side and a hook member on the other, and the downward projections on adjacent cross partitions are staggered so that a hookless tab alternates with a hook member. 45

In addition to the outer hooks and slots in 50

the cross partitions and bottom members, the inner bottom sections 16 and 18 are provided with openings 33 and 34, respectively. At the ends of the carton each of the bottom sections 16 and 18 is provided with openings, while interiorly of the carton the openings 33 and 34 are arranged in staggered relation. As shown in Fig. 3, the cross partition is provided with a central hook member 35 extending through the opening 33 and the section 18 rests against a braced portion 36. The hooks 35 and braced portions 36 are arranged in staggered relation interiorly of the carton and as shown in Fig. 5 these elements are arranged oppositely from the positions shown in Fig. 3. 15 The hook members on the center of the cross partitions are arranged to point in the same direction as the hook members on the outer portions of the cross partitions. Thus, as shown in Figs. 3 and 4, the hooks 31 and 35 point in the 20 same direction on each cross partition interiorly of the carton. The end cross partitions are provided with reduced hook portions 37 which extend through the end openings 34.

By arranging the hooks and slots in the manner described, it is possible to produce relative inward motion of the bottom member along score lines 17 and 20, whereby to produce an interlock between the hook members and the slots in the bottom section, and at the same time the bottom 25 member is adequately supported. The staggered hooks and brace portions act in a complementary fashion and produce a balance of support for eggs positioned in the container.

Various changes and alterations are possible 30 from the structure shown and described without departing from the scope of the invention and 35

such modifications are intended to be included in the appended claims.

I claim:

1. In a cellular carton of the type described, front and rear walls, cross partitions extending between said walls, and a cushion bottom section having front walls provided with openings for receiving projections on said cross partitions, said cross partitions having hook members arranged in staggered relation and engaging said bottom member in cushion-forming position through the openings therein. 5 10

2. In a cellular carton of the type described, front and rear walls, cross partitions extending between said walls, a plurality of bottom sections of substantially inverted V-shape having hook-receiving openings beneath said cross partitions, and hook members arranged in staggered relation on said cross partitions engaging said bottom sections through the openings therein and maintaining the same in cushion-forming position. 15 20

3. In a cellular carton of the type described, front and rear walls, two bottom sections of substantially inverted V-shape forming two outer channels and a central channel, said bottom sections having cross partition-receiving openings, and a series of cross partitions extending between the front and rear walls, each of said cross partitions having a central and an outer hook portion engaging said bottom section through the openings therein and the hooks on adjacent cross partitions being arranged in staggered relation. 25 30

JOHN ALLAN. 35
